Patented Nov. 16, 1965

202,895

COMPRESSION DEAD-END CONNECTOR

Henry William Tiernan, Jr., King of Prussia, Pa., assignor
to AMP Incorporated, Harrisburg, Pa.

Filed Nov. 18, 1964, Ser. No. 82,679

Term of patent 14 years

(Cl. D26—1)

FIGURE 1 is a perspective view of a compression dead-end connector showing my new design;
 FIGURE 2 is a side elevational view thereof;
 FIGURE 3 is a front end view thereof;
 FIGURE 4 is a rear end view thereof;
 FIGURE 5 is a top plan view thereof; and
 FIGURE 6 is a bottom plan view thereof.

I claim:

The ornamental design for a compression dead-end connector, as substantially shown.
